UNITED STATES PATENT OFFICE.

MAX OEHLER, OF RICHTFIELD, IDAHO.

MECHANICAL TOY.

1,136,707.

Specification of Letters Patent. Patented Apr. 20, 1915.

Application filed July 18, 1914. Serial No. 851,710.

To all whom it may concern:

Be it known that I, MAX OEHLER, a citizen of the United States, and residing at Richfield, in the county of Lincoln and State of Idaho, have invented certain new and useful Improvements in Mechanical Toys, of which the following is a specification.

This invention relates to toys, and more particularly, to mechanical or walking toys.

One of the objects of this invention is, to provide a novel toy which will travel on an inclined plane by gravity, without any other means of propulsion.

Other objects are, to provide a device which is simple in construction, cheap to manufacture, which consists of a few parts, and which will not get out of order.

Further objects will appear from the detail description taken in connection with the accompanying drawing, in which:

Figure 1 is a side elevation, partly in section, illustrating an embodiment of this invention. Fig. 2 is a section on the line 2—2, Fig. 1, and, Fig. 3 is a section on the line 25 3—3, Fig. 1.

Referring to the accompanying drawing, 10 designates a body which may be formed to resemble any suitable animal. This body is provided with a series of legs, in this case 30 four, designated 11, 12, 13 and 14. The forward legs 11 and 12 are attached to wire supports 15 and 16 which pass through slots 17 and 18 in the body and are pivoted on a cross pin 19 at the upper end of the body.

35 The supports 15 and 16 converge after they enter the body, so that their pivotal points will be close together transversely of the body and near the medial line, as shown in Fig. 3. The rear legs 13 and 14 have sup-

40 ports 20 and 21 which pass through slots 22 and 23 in the lower wall of the body and are pivoted to a cross pin 24 in the upper end of the body. The supports, in this case, are of the same form as the supports 15 and

45 16 shown in Fig. 3, and their pivotal points are also arranged close together. The legs are thus pivoted in pairs at the forward and rear ends of the body, so as to swing freely forwardly and backwardly with respect to

50 the body, and these legs are preferably weighted with metal. The parts are so constructed that when the toy sets on an inclined plane 25, as shown in Fig. 1, the front legs 11 and 12 will tend to swing forwardly by gravity to a vertical position until arrested by the ends of the slots. The rear

legs 13 and 14 also tend to swing forwardly by gravity in the same manner.

It will be noted that the pivotal connections of the legs to the body are near the top 60 of the body and, therefore, considerably above its center of gravity. It will also be noted that, in view of the fact that the pivotal connections are placed close together transversely of the body, the pivotal connections will be, in fact, nearly directly over the center of gravity of the body. If, therefore, the body is moved to the right and left side-wise, this body will begin to oscillate on the lower ends of the legs, so as to cause first 70 the legs on the right side to be raised from the supporting surface while the body is supported on the left side, and then cause the legs on the left side to be raised while the body is supported by the legs on the 75 right side. This toy will walk with distinct steps in the following manner.

Referring to the position of the parts, as shown in Figs. 1, 2 and 3, with the body resting on the legs on the left side, and with 80 these legs back so that their supports will engage the rear ends of the slots, the legs 12 and 14, being now raised, will be moved forwardly by gravity until arrested by the forward ends of the slots. The body will now 85 turn over to the right until it rests on the right legs, 12 and 14 while the left legs 11 and 13 are raised. This will cause the body to move forwardly on the right legs 12 and 14 to the position shown in dotted lines, Fig. 90 1, while the left legs 11 and 13, which are now raised, will move forwardly by gravity to the positions shown in dotted lines, Fig. 1. The body will then oscillate again to the left so as to cause it to be supported by the 95 legs 11 and 13, and it will move forwardly thereon, while the legs 12 and 14, which have been raised from the surface, will move forwardly by gravity. The oscillations of the device will thus be analogous to 100 those of a ballistic pendulum having a plurality of points of suspension. The body will first oscillate back and forth on one pair of legs until the other pair strike, and then back and forth on the other pair. Such 105 oscillations on two distinct centers will not only be more sustained, but will be more uniform than by having the bottoms of the legs in the nature of a substantially continuous rolling surface. Such oscillations about a 110 plurality of oscillating centers requires, for sustained operation that the center of grav-

ity of the oscillating body be below the pivotal points of attachment of the legs. It will thus be seen that the figure walks with distinct steps down the incline, this walking 5 action being accomplished by gravity alone. The body will oscillate as it moves down the incline, and it is not even necessary to give it a start. Moreover, the lateral oscillating movement is kept up by gravity in the same 10 manner that a pendulum is oscillated. This is brought about by pivoting the body to the legs above the center of gravity of the body, and by bringing the pivotal points close together and practically in the medial line of 15 the body and above its center of gravity.

It is obvious that various changes may be made in details of construction without departing from the spirit of this invention, and it is, therefore, to be understood that 20 this invention is not to be limited to the specific construction described and shown.

Having thus described the invention, what is claimed is:

1. A toy comprising a body, a pair of legs 25 pivoted to the forward end of said body, and a pair of legs pivoted to the rear end of said body, said legs being constructed and arranged on said body for free forward and backward movement with respect to said 30 body, the ends of said legs forming distinct centers of oscillation, and said body being adapted to oscillate laterally about the ends of the legs, whereby said legs are caused to move by gravity to simulate an animal in 35 walking.

2. A toy comprising a body, pairs of legs pivoted to the forward and rear ends of said body and above its center of gravity and adapted for free forward and backward 40 movement with respect to said body, the ends of said legs forming distinct centers of oscillation, and said body being adapted to oscillate transversely on the ends of said legs, whereby said legs are caused to move 45

by gravity to simulate an animal in walk- 45 ing.

3. A toy comprising a body, pairs of legs pivoted to the forward and rear ends of said body and adapted for free forward and backward movement with respect to said 50 body, the pivotal ends of the legs of a pair being closer together than the lower ends thereof, and said body being adapted to oscillate transversely on the lower ends of said legs, whereby said legs are caused to move 55 by gravity to simulate an animal in walking.

4. A toy comprising a body, pairs of legs pivoted to the forward and rear ends of said body and adapted for free forward and 60 backward movement with respect to said body, the pivots of said legs being above the center of gravity of said body and the pivotal ends of the legs of a pair being closer together than the lower ends thereof, said 65 body being adapted to oscillate transversely on the lower ends of said legs, whereby said legs are caused to move by gravity to simulate an animal in walking.

5. A toy comprising a body, pairs of legs 70 pivoted to the forward and rear ends of said body and above its center of gravity and adapted for free forward and backward movement with respect to said body, the pivotal ends of the legs of a pair being 75 closer together than the lower ends thereof, the ends of said legs forming distinct centers of oscillation and said body being adapted to oscillate transversely on the ends of said legs, whereby said legs are caused 80 to move by gravity to simulate an animal in walking.

In testimony whereof I affix my signature in the presence of two witnesses.

MAX OEHLER.
